UNITED STATES PATENT OFFICE.

FRED C. TRUESBURY, OF ROCKFORD, ILLINOIS, ASSIGNOR TO J. L. CLARK MANUFACTURING COMPANY, OF ROCKFORD, ILLINOIS, A CORPORATION OF ILLINOIS.

SIFTER-TOP CLOSURE.

1,153,356.

Specification of Letters Patent. Patented Sept. 14, 1915.

Application filed January 21, 1914. Serial No. 813,361.

To all whom it may concern:

Be it known that I, FRED C. TRUESBURY, a citizen of the United States, residing at Rockford, in the county of Winnebago and 5 the State of Illinois, have invented certain new and useful Improvements in Sifter-Top Closures, of which the following is a specification.

This invention relates to closures for containers adapted to contain pulverulent or 10 granular material, particularly when it is desired to sift or sprinkle the substances out of the container and also at times to pour out larger quantities.

15 The closure which I show and describe herein as an exemplification of my invention is so constructed that the sifter is adapted not only to open and close the sifting apertures in the container top, but also to open 20 and close a pouring opening. When the sifter is in one position the container is closed, when in another position the sifting apertures are open and the pouring aperture closed, and when in a third position or 25 entirely removed the pouring aperture is open.

30 In the accompanying drawings Figure 1 is a perspective view of a container which embodies features of my invention and which shows the container with its pouring aperture open. Fig. 2 is a cross section along the line 2—2 of Fig. 1. Fig. 3 is a 35 cross section similar to Fig. 2 but of a modified form of container top and sifter closure. Fig. 4 is a plan view of an embodiment of the preferred form of my invention.

Referring to Figs. 1, 2 and 3, the top 1 of the container 2 may be attached to the sides 3 by any well-known or preferred 40 means, for example, by crimping the flanges 4 upon the upper edges of the sides 3 of the container. Near the central portion of the top 1 is an upwardly projecting flange 5 elevating a portion 1^a of the top and 45 adapted to receive the sifter closure 6. In the elevated portion of the top is the opening 7 through which large quantities of the substance may be passed into the container or removed therefrom. The sifter closure 50 6 has on each side thereof downwardly and inwardly extending flanges 8 which respectively project into grooves 5^a formed in the flanges 5 of the top and so adjusted that the

sifter closure may be readily slid along the upper portion of the flanges 5 so as to respectively close or open, as desired, the pouring or the sifting apertures. 55

In addition to the pouring aperture 7 are sifting apertures 9. When the sifter closure 6 is in the position shown in Fig. 1, the 60 sifting apertures are closed as indicated and the pouring aperture is opened. When, however, the sifter closure is pushed farther onto the elevated portion 1^a of the top, the 65 pouring aperture 7 is closed and the sifting apertures 9 in the top register with apertures 10 in the closure, so that the contents of the container may be sifted through the registering openings. By sliding the closure 70 onto the top until the downwardly projecting flange 14 on one end of the closure comes against flange 5, apertures 9 and 10 will no longer register and at the same time the opening 7 will be closed and thus the 75 container itself will be entirely closed. 75

If desired, instead of the inwardly projecting groove 5^a in the container top, this, or a corresponding portion of the flange 5 may be pressed outwardly so as to form a ridge 11 on each side of the flange 5 as 80 indicated in Fig. 3. And the downwardly and inwardly projecting flanges 12 of the closure may be formed so as to extend below the ridge 11, so that the closure in that manner will be slidably mounted on the top. 85 By these means an exceedingly simple and effective sliding connection is obtained between the closure and the top so that the closure may be readily moved to any position desired on the top, or may be entirely 90 removed.

An upwardly extending circular ridge 13 may be pressed into the closure. By placing the finger within the space bounded by the ridge the closure may be more readily 95 slid into the desired position.

Fig. 4 shows an alternative construction of top which exemplifies the preferred form of my invention. By positioning the sifting apertures 9^a in a single row on one side of the pouring aperture 7^a, and locating the apertures 10^a correspondingly, a larger 100 pouring aperture is provided for by removing the closure entirely from the top, and the shape of the pouring aperture is better 105 adapted to receive a spoon or other flat in-

strument. The large size of the aperture 7^a also facilitates the operation of filling the container.

I claim as my invention:

- 5 1. In a container, a sheet-metal top having an integral perpendicular flange extending upwardly therefrom and defining an elongated space, a flat horizontal portion integral with the upper edge of said flange and partially closing the space defined by the flange, said horizontal portion defining a relatively large opening and also being provided with a series of sifting apertures, a closure plate overlying the upper edge of said flange and said horizontal portion and having a series of sifting apertures arranged to register at times with the other series of apertures, the portions of the flange at opposite sides of said space being straight and parallel and each of said portions of the flange being provided with an indentation of less width than the height of the flange to form longitudinal guideways, and depending flanges on the opposite straight edges of said closure plate having their edges bent inwardly to engage said guideways, whereby the closure plate will be guided for rectilinear sliding movement to uncover said relatively large opening or to bring said two series of sifting apertures into register.
- 10 2. In a container, a top having a relatively large elongated aperture, a closure mounted on said top to slide rectilinearly lengthwise of said aperture, said top having a row of
- 15
- 20
- 25
- 30

comparatively small apertures therethrough adjacent to and substantially parallel with said large aperture, said closure having a corresponding row of small apertures arranged to register with the row in the top, 40 said closure being slidable to bring the two rows of apertures into registry and also being movable to uncover the large elongated aperture.

3. In a container, a sheet metal top having 45 an integral elevated portion of elongated shape consisting of a flange and a horizontal portion at the upper edge of the flange, there being a relatively large elongated opening alongside said horizontal portion, and the latter having a row of 50 comparatively small apertures running parallel to the longer dimension of said large opening, the said flange at opposite sides of the elevated portion being straight and parallel 55 and being bent to provide guideways, a closure plate overlying said elevated portion, and depending flanges at opposite sides of said plate engaging said guideways, whereby the plate will be slidable rectilinearly 60 lengthwise of said elongated portion, the plate having a row of small apertures adapted to register with the apertures in the horizontal part of said elevated portion.

In testimony whereof I affix my signature 65 in presence of two witnesses.

FRED C. TRUESBURY.
